UNITED STATES PATENT OFFICE.

JAMES C. ALLAN, OF RIDDLESBURG, PENNSYLVANIA.

AUTOMATIC MINE-DOOR.

1,242,411.

Specification of Letters Patent.

Patented Oct. 9, 1917.

Application filed August 15, 1916. Serial No. 115,052.

To all whom it may concern:

Be it known that I, JAMES C. ALLAN, a citizen of the United States, residing at Riddleburg, in the county of Bedford and State of Pennsylvania, have invented certain new and useful Improvements in Automatic Mine-Doors, of which the following is a specification.

This invention contemplates an improved mine door and has as its primary object to provide a construction wherein the door will be automatically opened by a mine car, motor or locomotive approaching the door from either direction and wherein, upon the passage of a car through the door, the said door will be automatically closed.

The invention has as a further object to provide an arrangement wherein the door will be positively opened upon the approach of a car and held open until the car, motor or locomotive has passed through the door and wherein the door will normally be positively held closed.

A still further object of the invention is to provide an improved operating mechanism for the door.

And the invention has as a still further object to provide an arrangement wherein the door will be effectually cushioned upon the closing of the door.

Other and incidental objects will appear as the description proceeds and in the drawings wherein I have illustrated the preferred embodiment of the invention and wherein similar reference characters designate corresponding parts throughout the several views:

Figure 1 is a plan view of the door and illustrating the operating mechanism therefor at one side of the door.

Fig. 1^a is a similar view illustrating the operating mechanism at the opposite side of the door,

Fig. 2 is a plan view particularly illustrating the connection between the sections of the door and illustrating the said sections moved to open position,

Fig. 3 is a detail perspective view showing the door closed and illustrating the crank arm employed for opening and closing the door and the engagement between the said arm and one of the sections of the door,

Fig. 4 is a detail sectional view particularly illustrating the mounting of the com-

bined cushioning and sealing strip for the door,

Fig. 5 is an end elevation partly in section and particularly showing the type of supporting bracket employed for the rock shaft of the door operating mechanism,

Fig. 6 is a detail sectional view illustrating the mounting of the operating bars or levers of the said mechanism,

Fig. 7 is a fragmentary perspective view showing the type of hinge connection employed at coacting ends of the operating levers, and

Fig. 8 is a fragmentary plan view showing the coacting ends of the said levers connected.

My improved door may be employed in connection with a mine track of any conventional type and in the drawings I have illustrated such a track at 10. Mounted adjacent the outermost rail of the track is a guard rail 11, this rail being arranged to prevent the lateral shifting of a mine car upon the track when the wheels of the car engage the levers of the door operating mechanism employed, as shall be presently described. Arranged to extend over the track is a door frame including vertical side members 12. These members are preferably formed of suitable channel iron as particularly shown in Figs. 1 and 2 of the drawings and extending inwardly from the said side members, at the top of the door, is a laterally directed substantially V-shaped head-piece 13 preferably formed of angle iron and connected to the side members 12 in any suitable manner.

The door is formed of coacting sections 14 and 15 respectively hingedly mounted upon the side members 12 of the door frame and arranged to abut the head-piece 13 with the free edges of the door meeting to close the door opening. Connected to the outer face of the head piece 13 is a channel strip 16 of the type illustrated in Fig. 4 of the drawings. The side members 12 of the door frame are also provided with similar strips 17 and seated in the said strips 16 and 17 is a combined sealing and cushioning element 18. This cushioning element may be formed of rubber or any other suitable material and is disposed to contact with the longitudinal inner edges of the sections of the door as well as with the upper margins thereof for cushioning the door sections when moved.

to closed position as well as to provide a tight joint between the door sections and the door frame to prevent the passage of air through the door. Mounted upon the section 14 of the door is a hinge bracket 19 while a similar hinge bracket 20 is mounted upon the door section 15. Pivotally mounted upon the brackets 19 and 20 is a connecting rod 21 which is formed of sections adjustably connected by a sleeve 22 operable for regulating the normal relative position of the door sections 14 and 15. Mounted upon the outer side of the door section 15 to project laterally therefrom is an obliquely arranged link 23 having its lower extremity arranged adjacent the free longitudinal edge of the said door section and inclined upwardly with its upper end arranged adjacent the opposite longitudinal edge of the said section on the door. The purpose of this link will presently appear.

As will now be best observed upon reference to Figs. 1 and 1^a of the drawings, certain of the ties upon opposite sides of the door are extended at one side of the track 10 and mounted upon the outer extremities of the said ties are a plurality of shaft hangers 24 of the general type illustrated in detail in Fig. 5 of the drawings.

Rotatably mounted upon the said hangers to extend parallel with the track 10 is a rock shaft 25 projecting upon opposite sides of the door. The rear legs of the terminal hangers 24 are, at points below the rock shaft 25, provided with bearings 26 supported, as more particularly shown in Fig. 5 of the drawings, by auxiliary legs 27. Mounted in the said bearings are suitable stub shafts to which are connected rock levers 28. Connected to the extremities of the rock shaft 25 are depending crank arms 29 and pivotally connecting the said crank arms with the upper extremities of the levers 28, are links 30.

Mounted to extend longitudinally of the track 10 upon opposite sides of the door are pairs of coacting operating levers, the corresponding levers of each pair being designated 31 and 32 respectively. The outermost levers 31 are, at their outer extremities, loosely connected to posts 33 mounted upon adjacent ties of the track 10 while the meeting ends of the levers 32 are pivotally mounted upon a similar post 34 arranged adjacent the door. Supporting the said pairs of levers intermediate the ends thereof, are a plurality of stools or brackets 35 mounted upon the adjacent ends of the ties of the track with the inner extremities of the said brackets connected, as more particularly shown in Fig. 5 of the drawings, to the outermost track rail. The brackets 35 are of a height substantially equal to that of the outermost rail of the track to support the inner extremities of the levers 31 and 32.

for movement over the said rail and to reduce friction between the parts, I provide the said levers each with a plurality of roller bearings 36. The roller bearings 36 are preferably of the type illustrated in Fig. 6 of the drawings, it being observed that the levers 31 and 32 are preferably formed of angle irons with one flange thereof arranged to confront the brackets 35 and with the bearings 36 carried by the said flange to ride over the said brackets. Pivotally connecting the coacting ends of the levers 31 and 32 of each pair of the said levers is a hinge joint of the type illustrated in detail in Fig. 7 of the drawings. This joint includes an element 37 secured to the upstanding flange of the adjacent lever 31 and provided with spaced hinge lugs 38. Secured to the upstanding flange of the adjacent lever 32 is an element 39 having an arm 40 projecting laterally from the inner extremity thereof with the said arm adapted to fit between the hinge lugs 38 of the element 37 and provided with an opening for receiving a pivot pin 41 passing through the said hinge lugs and through the said arm for swingingly connecting the levers. Pivotally connecting the outer extremities of the arms 40 of the said hinge joints with the lower extremities of the rock levers 28 upon the terminal hangers 24, are connecting rods 42 which are formed in sections adjustably connected by sleeves 43 operable for regulating the normal position of the inner extremities of the pairs of levers 31 and 32 with respect to the outermost rail of the track.

Connected to the rock shaft 25 adjacent one extremity thereof, is a counterpoise 43' having a dash-pot 44 associated therewith and connected with the said shaft opposite the door section 15 is a crank arm 45 extending toward the said door section and provided at its free extremity with an upstanding post or lug 46 engaging freely within the link 23, the purpose of this link now being apparent. The crank arm 45 is adjustable circumferentially of the shaft 25 for regulating the normal position of the said arm within the link 23 and is mounted to travel in a plane at an acute angle to the said link.

As will be observed, the pairs of operating levers 31 and 32 are, when the door is closed, arranged to project in normal position over the outermost rail of the track 10 for engagement with the wheels of a car passing over the said track and to which position, the said levers are normally urged by the counterpoise 43'. A car approaching the door upon the track 10 in the direction of the arrow upon Fig. 1 of the drawings, will first engage the outermost operating lever 31 of the pair of said levers arranged upon the adjacent side of the door to shift

the said levers laterally and outwardly over the outermost rail of the track and consequently, through the medium of the adjacent connecting rod 42 rock the lever 28. 5 Movement of this lever will, in turn, as will be clear, rock the shaft 25 to raise the counterpoise 43' and rotate or lift the crank arm 45 upwardly. Upward movement of the crank arm 45 will, in turn, cause the lug 46 thereof to ride upwardly within the link 33 upon the door section 15 to swing the said door section outwardly upon its hinges. Outward movement of the door section 15 will, through the medium of the 10 connecting rod 21 be communicated to the door section 14 so that upon the shifting of the said operating lever 31 by the car as the car advances toward the door, the sections of the door will be simultaneously 15 swung to open position. In this connection, it will be noted that the hinge bracket 19 upon the door section 14 is located outwardly a considerable distance from the pivotal axis of the said door section while the hinge bracket 20 is located immediately 20 adjacent to the pivotal axis of the door section 15. Consequently, when the hinge bracket 20 is swung in an arcuate path upon the door section 15, it will operate upon the hinge bracket 19 upon the door section 14 through the medium of the connecting rod 21 to move the said door section 14 to open 25 position. Closing movement of the door section 15 will, of course, in a similar manner act to close the door section 14.

The car after having passed over the outermost operating lever 31 when traveling in the direction indicated will then engage the adjacent operating lever 32 to hold the 30 door open until the car has passed through the door when it will then contact with the operating lever 32 upon the opposite side of the door to continue to hold the door open. Thus, should there be a train of cars passing 35 through the door, the door would be held open until the last car of the train has passed the door.

The car upon having passed the last mentioned lever 32 will then pass the adjacent 40 outermost lever 31 when the counterpoise 43' will immediately act upon the shaft 25 to swing the crank arm 45 downwardly for closing the door and at the same time, shifting the pairs of levers 31 and 32 upon opposite sides of the door to normal position 45 projecting over the outermost rail of the track ready for engagement with the next car passing over the track. In this connection, attention is directed to the fact that the counterpoise 43' is arranged to normally 50 act upon the shaft 25 for urging the crank arm 45 toward the door section 15 and consequently holding the door closed, it being understood, of course, that the dash-pot 44 55 is arranged to coöperate with the cushioning

element 18 upon the door frame for cushioning the door sections 14 and 15 upon the movement thereof to closed position. As will now be clear, in view of the preceding description, a car passing over the track 10 60 toward the door in the direction of the arrow upon Fig. 1^a of the drawings will act upon the adjacent pair of operating levers 31 and 32 in a manner similar to that previously described with reference to the other 65 pair of said levers for opening the door when the car, after having passed through the door, will act upon the operating levers at the adjacent side thereof for holding the door open until the said car or train of 70 cars has completely passed through the door. It will, therefore, be seen that I provide an arrangement wherein the door will be automatically opened upon the approach of a car toward the door from either direction 75 and wherein, after the car has passed through the door, the said door will be automatically closed. Furthermore, it will be seen that I provide an arrangement wherein in the door will be positively moved to open 80 position and will also be positively held in closed position.

Having thus described the invention, what is claimed as new is:

1. A device of the character described including a door, and an operating mechanism therefor, said mechanism including a pair of coacting operating levers operable by a car approaching the door, supporting brackets for said levers, anti-friction bearings carried by the levers for engagement with said brackets, a crank arm operatively engaging the door, and an operative connection between the said crank arm and the said levers for shifting the said arm to open the door upon the actuation of the levers.

2. A device of the character described including a door, and an operating mechanism therefor, said mechanism including a pair of coacting operating levers operable by a car approaching the door, a rock shaft, a crank arm carried by said shaft and operatively engaging the door, a counterpoise carried by the shaft and normally acting thereon to hold the door closed, a dash-pot associated with said counterpoise, and an operative connection between the said shaft and the said levers for swinging the crank arm to open the door upon the actuation of the said levers with the said dash-pot adapted to cushion the closing movement of the door.

3. A device of the character described including a door, and an operating mechanism therefor, the said mechanism including a pair of coacting operating levers, a hinge connection between the meeting ends of said levers, said connection including an element carried by one of the levers and provided with hinge lugs, an element carried by the other of said levers and provided with an

4
arm received between said lugs, and a pivot pin extending through the lugs and through said arm for pivotally connecting the levers, and an operative connection between said arm and the door for opening the door upon the actuation of the said levers.

4. A device of the character described including a door, and an operating mechanism therefor, the said mechanism including a 10 pair of coacting operating levers operable by a car approaching the door, a rock shaft, hangers for said shaft, a stub shaft carried by one of said hangers, a rock lever mounted upon said stub shaft, a crank arm carried by 15 the rock shaft, a link connecting said crank arm with said rock lever, a second link adjustably connecting the said first mentioned levers with the said rock lever, and an operative connection between the said rock shaft 20 and the door for opening the door upon the actuation of the said operating levers.

5. A device of the character described including a door frame, a door mounted upon the frame and normally projecting angularly therefrom, a link mounted upon the door and inclined upwardly thereon in a direction from the free edge of the door toward its inner edge, a pair of coacting operating levers, a rock shaft, a horizontally arranged crank arm extending substantially parallel to the door frame and normally at an acute angle to the plane of the door with the said arm engaging in the lower extremity of said link, and an operative connection between the said levers and the said shaft for swinging the said crank arm within the said link to open the door upon the actuation of the said levers.

6. A device of the character described including a door, and an operating mechanism therefor, said mechanism including a pair 40 of coacting operating levers, a rock shaft

arranged to extend at substantially right angles to the plane of the door frame, a horizontally arranged crank arm carried by said 45 shaft and slidably connected with the door with the said arm movable upwardly in a plane parallel to the plane of the door frame for opening the door, and an operative connection between the said shaft and the said 50 levers for swinging the said crank arm.

7. A device of the character described including a door, an inclined link carried thereby, and an operating mechanism for the door, the said mechanism including a 55 pair of coacting operating levers, a rock shaft, a horizontally arranged crank arm carried by said shaft and freely engaged with said link with the arm normally extending at an acute angle to the door and 60 movable upwardly to slide within the link from the lower extremity thereof toward the upper extremity of the said link for opening the door, and an operative connection between the said levers and the said 65 shaft for swinging the said crank arm.

8. A device of the character described including a door, and an operating mechanism therefor, said mechanism including a 70 pair of operating levers, a rock shaft, a horizontally arranged crank arm carried by said shaft and slidably connected with the door with the said arm movable upwardly for opening the door, an operative connection between the said shaft and the said levers, 75 and means acting upon the shaft for normally urging the crank arm to a position with the length thereof disposed in a horizontal plane with the said shaft and bearing at its inner extremity against the door 80 for holding the door closed.

In testimony whereof I affix my signature.

JAMES C. ALLAN. [L. s.]
